Primary Examiner — Karen S Acker*Assistant Examiner* — Elizabeth S Ko(74) *Attorney, Agent, or Firm* — Bill R. Nafeh(57) **CLAIM**

I claim the ornamental design for a mounting bracket, as substantially shown and described.

DESCRIPTION

FIG. 1 is an isometric view of a mounting bracket;

FIG. 2 is a left side view thereof;

FIG. 3 is a right side view thereof;

FIG. 4 is a top view thereof;

FIG. 5 is a bottom view thereof;

FIG. 6 is a front view thereof; and,

FIG. 7 is a rear view thereof.

The dashed lines in FIGS. 1 and 4 depict environment that forms no part of the claimed design.

The broken lines and areas within them depict portions of the mounting bracket that form no part of the claimed design.

1 Claim, 4 Drawing Sheets(56)
